UNITED STATES PATENT OFFICE.

PAUL RACZEK, OF NEW YORK, N. Y.

DESIGN FOR A CASE FOR COIN-CONTROLLED VENDING-MACHINES.

SPECIFICATION forming part of **Design No. 31,630**, dated **October 10, 1899**.

Application filed August 9, 1899. Serial No. 726,722. Term of patent 3½ years.

To all whom it may concern:

Be it known that I, PAUL RACZEK, a citizen of the United States, and a resident of the borough of Brooklyn, in the city and State of New York, have invented and produced a new and original Design for the Case of a Coin-Controlled Vending-Machine, of which the following is a specification, reference being had to the accompanying drawings, in which—

10 Figure 1 is a side view of my new design, and Fig. 2 is a plan view of the same.

The essential features of my new design consist in the figure of a hen and a basket in which the hen is sitting, said basket having 15 upright sides and a horizontal section of oblong quadrangular form with round corners and having a plain band around its lower part, as illustrated by the accompanying drawings of the case of a coin-controlled vending-20 machine of my new design.

In the said drawings, *a* designates the body of the basket, representing wicker-work. *b* designates the plain band around the lower part of the basket, and *c* designates the figure of the hen.

25

What I claim is—

The design for the case of a coin-controlled vending-machine, herein shown and described.

In testimony that I claim the foregoing as 30 my invention I have signed my name, in presence of two witnesses, this 3d day of August, 1899.

PAUL RACZEK.

Witnesses:

GEORGE BARRY, Jr.,
